(57) **CLAIM**

The ornamental design for a set of toilet partition hinges, as shown and described.

DESCRIPTION

FIG. 1 is a top left front perspective view of the upper portion of the lower hinge;

FIG. 2 is a bottom plan view of the upper portion of the lower hinge shown in FIG. 1;

FIG. 3 is a top left front perspective view of the lower portion of the lower hinge;

FIG. 4 is a bottom plan view of the lower portion of the lower hinge shown in FIG. 3;

FIG. 5 is a top, left, and front perspective view of the lower hinge of the set of toilet partition hinges showing the assembly of the upper and lower portions of the lower hinge shown in FIGS. 1 through 4;

FIG. 6 is a top left front perspective view of the upper portion of the upper hinge;

FIG. 7 is a bottom plan view of the upper portion of the upper hinge shown in FIG. 6;

FIG. 8 is a top left front perspective view of the lower portion of the upper hinge;

FIG. 9 is a top plan view of the lower portion of the upper hinge shown in FIG. 8; and,

FIG. 10 is a top, left and front perspective view of the upper hinge of the set of toilet partition hinges showing the assembly of the upper and lower portions of the upper hinge shown in FIGS. 6 and 9.

The features shown in dotted or broken lines do not form part of the claimed invention.

The claimed set comprises an upper hinge and a lower hinge. Each hinge has an upper portion and a lower portion. The lower hinge is shown in FIGS. 1 through 5 and the upper hinge is shown in FIGS. 6 through 10.
